UNITED STATES PATENT OFFICE.

WILLIAM H. PENSEYRES, OF BUFFALO, NEW YORK, ASSIGNOR, BY DIRECT AND MESNE ASSIGNMENTS, TO GEORGE HABERER, OF SAME PLACE, AND JOHN DANHEISER, OF HAMBURG, NEW YORK.

BACK-PEDALING BRAKE.

SPECIFICATION forming part of Letters Patent No. 634,700, dated October 10, 1899.

Application filed October 10, 1898. Serial No. 693,135. (No model.)

To all whom it may concern:

Be it known that I, WILLIAM H. PENSEYRES, a citizen of the United States, residing at Buffalo, in the county of Erie and State of New York, have invented certain new and useful Improvements in Bicycles, of which the following is a specification.

My invention relates to an improved bicycle, and particularly to the brake mechanism therefor, in which a brake is applied to the rear wheel by back-pedaling. It also relates to a ball-bearing-clutch device upon the rear hub for supporting the rear sprocket, so that it can rotate freely in one direction to provide means for coasting.

It also relates to certain details of construction, all of which will be fully and clearly hereinafter described and claimed, reference being had to the accompanying drawings, in which—

Figure 1 represents a side elevation of a bicycle, portions being in section to expose my improved brake mechanism. Fig. 2 represents an enlarged detached view of the rear sprocket and its clutch, the sprocket being in section to expose the grooves and balls. Fig. 3 is an enlarged section through the crank-shaft on or about line *a a*, Fig. 7, looking in the direction of the arrow *V*, the crank being omitted. Fig. 4 is an enlarged section through the crank-hanger and also through the crank-shaft and the clutch mechanism on or about line *b b*, Fig. 7, looking in the direction of the arrow *X*, the screws which hold the clutch mechanism together being shown to denote their position, also showing a portion of the bicycle-frame, the brake, and its supporting devices. Fig. 5 is a detached view of the notched ring. Fig. 6 is a section on or about line *c c* of Fig. 5 to illustrate the almost imperceptible concaved interior of the notched ring. Fig. 7 represents a section through the sleeve, the clutch mechanism, and the cones and sprocket, the shaft and its cranks being shown in full lines. Fig. 8 is a detached view of the brake, the inclosing case being shown in section to expose the interior mechanism.

In reference to the accompanying drawings 50 in detail like numerals represent like parts.

The bicycle is composed of the usual frame 1, handle-bars 2, front wheel 3, rear wheel 4, crank-hanger 5, saddle-post 6, and saddle 7, all of which are of well-known construction.

The crank-shaft is preferably formed in two sections 8 and 9, which are secured together by a sleeve 10, to the center or substantially the center of which is rigidly secured an enlargement or ring 11, and an annular ring 12, having a series of peripheral grooves 13, is supported upon the sleeve 10 by means of the supplementary ring 14 and the screws 15, which are passed through the supplementary ring 14, the grooved ring 12, and the ring 11, thus rigidly securing them all together and 65 to the shaft. A hardened-steel ball 16 is placed in each of the grooves 13, and an outer annular clutch-ring 17, having a peripheral depression or notch 18, is supported upon the balls 16. The rings 11 and 14 are larger in 70 circumference than the interior of the outer ring 17 and project over the sides of the same to prevent lateral displacement. The interior of the ring 17 is preferably concaved very slightly to provide a grooved track for 75 the balls, as shown in Fig. 6. It will readily be seen by reference to the drawings that the notched ring 17 will revolve easily around the grooved ring 12 when the shaft is rotated in the direction required to propel the bicycle 80 forward and that upon power being applied to turn the shaft in the contrary direction the balls will roll in the grooves and wedge themselves between the interior of the ring 17 and the grooves, and thereby rigidly lock 85 the ring 17 against independent rotation in that direction.

A support or standard 19 is detachably secured to the cross-brace 20 of the rear stay-tubes of the bicycle by means of the bolt 21. 90 This support 19 is provided with an opening through which the brake-rod 22 passes. A screw-threaded opening is located in the crank-hanger near the top thereof, within which the screw-threaded end 23 of the inclosing case 24 is supported.

The brake-spoon 25 is of the usual curved pattern and has an interiorly-screw-threaded tube 26, in which the screw-threaded end of the brake-rod 22 engages, thus providing 100

means for longitudinal adjustment. To lock the spoon in any position to which it may be adjusted, the lock-nut 27 upon the screw-threaded brake-rod is screwed firmly against the outer edge of the tube 26. The inclosing case 24 is provided with a screw-cap 28, which screws into the rear end thereof, said cap having a central opening through which the brake-rod passes. A coiled spring 29 is located within the inclosing case, with one end against the cap 28 and the other bent and inserted in an opening in the brake-rod, the office of which is to normally retain the brake-spoon in position away from the tire. The brake-rod extends through the inclosing case and into the interior of the crank-hanger, terminating in a reduced end portion 30, which fits in the notch 18 in the clutch-ring 17. The rear wheel is also provided with a clutch device to allow the rear sprocket to freely rotate in one direction independently of the hub. This device comprises the annular ring 31, having a series of peripheral grooves 32, preferably six in number, which is rigidly secured by any well-known means upon the hub. The sprocket-ring 34 is provided with a concaved interior forming an internally-encircling groove 35, and a series of balls 33 are introduced into the grooves 32 through an opening of sufficient size in the sprocket-ring located between two of its teeth. The office of these balls is to form wedges to lock the sprocket-ring against independent rotation when the bicycle is propelled forward and to provide an easy rolling bearing to allow the sprocket-ring to rotate freely upon the ring 31 and the bicycle to coast when the rotation of the shaft ceases. As portions of these balls are in both the groove 35 and the grooves 32, the balls also serve to support the sprocket-ring against lateral displacement. (See Fig. 2.) The opening in the sprocket-ring through which the balls are introduced is closed by means of the screw 36.

To limit the range of movement of the brake, and thus prevent the spoon from pressing too heavily against the tire, a nut 37 is placed upon the brake-rod in front of the standard or support 19, which can be rotated thereon to any position desired. Upon applying the brake this nut strikes against the support, and thus limits its forward movement.

The two sections of the divided crank-shaft are preferably secured together, as shown in Fig. 7, the section 8, which I term the "sprocket-supporting" section, being provided at its junction with its crank with a smooth-surfaced portion 38, upon which the sprocket 39 is pressed. This portion 38 merges inwardly in a screw-threaded section 40, having a right-hand screw-thread, upon which the cone 41 is screwed firmly against the sprocket to hold it in place, and this right-hand screw-threaded portion in turn merges in a left-hand screw-threaded portion 40^a, with which

the screw-threaded end of the sleeve engages. The purpose of these two oppositely-extending screw-threaded portions is to provide means for firmly and rigidly locking the sleeve to that section of the shaft, and especially against independent rotation of the sleeve upon the shaft when the brake is applied. The opposite end of the sleeve is secured to the other shaft portion 9 by the locking-cone 42, which is supported upon balls 43 to afford easy rotation.

The brake is applied by "back-pedaling," the backward revolution of the crank-shaft causing the clutch device thereon to operate to prevent the independent rotation of the notched ring and the notch in said ring forcing the brake-rod backward and the brake-spoon against the tire.

The assembling and dismounting of the device will be easily understood from the foregoing.

To prevent the independent rotation of the sprocket upon the shaft, a screw-bolt 44 is passed through the sprocket and into an opening in the crank.

The reduced end portion 30 of the brake-rod 22, which is seated in the notch, is preferably flat to prevent the rotation of the rod and the turning of the spoon from its vertical position.

I claim as my invention—

1. In a bicycle, the combination with the frame, the wheels, a clutch device for forward driving, a crank-hanger having a screw-threaded opening in its upper rear portion, and a crank-shaft rotatably supported in the crank-hanger, of a clutch mechanism mounted upon the shaft and supporting a notched outer ring, a tubular inclosing case having a reduced exteriorly-screw-threaded inner end engaging in the screw-threaded opening in the crank-hanger and an interiorly-screw-threaded outer end, a cap having a reduced screw-threaded portion fitting in the interiorly-screw-threaded portion of the inclosing case, an outer flange and a central opening, a supporting-standard, screws for detachably securing said standard to the frame, a brake-rod passing through said standard, the inclosing case and the central opening in the cap and having its forward end fitting in the notch in the outer ring in the clutch mechanism and its rear end screw-threaded, a brake-spoon having a screw-threaded tubular portion fitting upon the screw-threaded rod, a lock-nut for securing said spoon at any position to which it may be adjusted upon said rod, an adjusting-nut upon the brake-rod in front of said standard for regulating the rearward thrust of the brake and a spring within the inclosing case having one end secured to the rod and the other abutting against the cap for holding the brake normally away from the tire, as set forth.

2. In a bicycle having a brake adapted to be set by back-pedaling, the combination with the frame, wheels, and a clutch device

for forward driving, of a hanger having a crank - shaft rotatably supported in said hanger, and a ball-bearing clutch fitted on said shaft, the outer member of the clutch consisting of an annular ring having a grooved inner bearing adapted to operate on the balls of the clutch, the periphery of the said annular ring being provided with a rearwardly-inclined notch; a screw-threaded opening in the rear of the hanger, a tubular spring-in-
closing case having a reduced screw-threaded end screwing into said opening, a brake-rod passing through the tubular casing and the opening in the hanger having a screw-thread-

ed rear end and a reduced forward end fitting in the peripheral notch in the annular ring, a spiral spring within the casing encircling the rod, a brake-spoon having a forward extension provided with a screw-threaded opening into which the screw-threaded rear end of the brake-rod screws, and a lock-nut upon said brake-rod adapted to screw against the extension of the spoon to lock it to the rod, as set forth.

WILLIAM H. PENSEYRES.
